UNITED STATES PATENT OFFICE

2,541,783

INVALID LIFT

George Q. Rust, Wharton, Tex.

Application June 6, 1947, Serial No. 752,901

1 Claim. (Cl. 5—67)

1

This invention relates to an attachment for a hospital bed and has for its primary object to lift a patient clear of the bed without altering his position.

Another object is to enable the body of a patient occupying the lift to be elevated into a sitting or partially sitting posture, and held in such position during his transportation on the lift.

A further object is to facilitate the use of a bed-pan by a bedridden patient without subjecting the patient to discomfort.

The above and other objects may be attained by employing this invention which embodies among its features a lift frame adapted to rest on the frame of a hospital bed, a trunk supporting and elevating frame pivoted at one end intermediate opposite ends of the lift frame and adapted to overlie the head end of the lift frame, a notched supporting bar pivoted at one end to each side of the trunk supporting and elevating frame intermediate its ends, pins projecting laterally from opposite sides of the lift frame near the head end thereof for entrance into the notches in the supporting bars, a lift sheet extending transversely of the lift frame between the foot end and the trunk supporting and elevating frame and a lift sheet extending transversely of the trunk supporting and elevating frame.

Other features include a removable sheet extending transversely of the lift frame adjacent the pivotal point of the trunk supporting and elevating frame, and the pivots of the trunk supporting and elevating frame substantially coinciding with the pivots of the trunk supporting and elevating frame of the bed whereby the trunk supporting and elevating frame of the lift frame may be moved in unison with that of the bed frame.

In the drawings:

Figure 1 is a plan view of an invalid lift embodying the features of this invention and showing the same mounted on a hospital bed;

Figure 2 is a side view of Figure 1;

Figure 3 is a view similar to Figure 2 illustrating the trunk supporting and elevating frame of the bed in elevated position, with the trunk supporting and elevating frame of the lift frame resting thereon;

Figure 4 is a fragmentary enlarged end view of the lift frame, showing portions in section to more clearly illustrate certain details of construction;

Figure 5 is an enlarged transverse sectional

2

view taken substantially along the line 5—5 of Figure 3;

Figure 6 is an enlarged fragmentary perspective view of the foot end of the lift frame and corner of the bed, and

Figure 7 is a perspective view of the supporting hook for the foot end of the lift frame.

Referring to the drawings in detail, a bed designated generally 10 is equipped with the conventional head board 11 and foot board 12 joined by conventional side rails 13 between which is pivoted as at 14 intermediate their ends the trunk elevating frame 15 of the bed. The frame 15 is raised and lowered by conventional elevating mechanism 16 operated through the medium of a hand crank 17 which is generally located at the foot of the bed. The structure so far described is conventional with hospital beds and resting on the bed frame is a conventional jointed spring 18 and jointed mattress 19.

My invention embodies a lift frame or a horizontal limb supporting section designated generally 20 which comprises side rails 21 held in spaced parallel relation at opposite ends by telescopic end bars or rails 22 which are held after adjustment against longitudinal movement by suitable set screws 23. As illustrated, the side rails 21 bend downwardly as at 24 near the head end of the bed so that opposite ends of the telescopic end bars 22 at the head end of the bed will rest directly on the side rails 13 of the bed frame. Secured as by clamps 25 to the foot posts of the foot 12 of the bed frame 10 are supporting hooks 26 carrying arms 27 with upturned hook members 28 at their free ends. The arms 27 form supporting elements for the telescopic cross bar 22 at the foot end of the bed so as to compensate for the downturned portions 24 at the head end of the bed in holding the patient level.

Attached to opposite ends of the extensible bars 22 are upwardly extending brackets 29 carrying at their upper ends eyes 30 to which hoist cables are adapted to be coupled for lifting the lift frame.

Pivoted as at 31 to each side rail 21 intermediate its ends is a side rail 32 of a trunk supporting and elevating frame designated generally 33. The ends of the side rails 32 of the frame 33 remote from the pivots 31 are joined by an extensible cross bar 34 which corresponds to the cross bar 22 at the head end of the bed and is held in adjusted position by means of set screws 35. As illustrated in Figure 4 when the frame 33 is in lowered position the cross bar 34 lies directly on the cross bar 22 at the head end

of the bed, with the side bars 32 of the frame 33 partially embracing the side rails 21 lying between the pivots 31 and the head end of the bed. As illustrated in Figures 2 and 3 the pivots 31 are substantially coincident with the pivots 14 so that as the frame 15 of the bed is elevated by the elevating mechanism 16 operated from the crank 17, the frame 33 will swing upwardly as suggested in Figure 3. In order to hold the frame 33 in elevated position I pivotally attach as at 36 to each side rail 32 near the cross bar 34 an arm 37 provided with spaced notches 38 which are adapted to receive laterally extending pins 39 carried by the side rails 21 near the head end of the bed. It will thus be seen that as the frame 33 is elevated the pins 39 may be entered into the various notches 38 so that when the lift frame 20 is lifted from the bed, the frame 33 will stay in the position selected.

In order to support a patient on the lift frame when it is elevated from the bed I provide a lift sheet 40 which extends transversely of the lift frame and across the top of the mattress 19 from a point adjacent the foot of the bed to a point near the pivots 31. A similar lift sheet 41 extends transversely across the lift frame from a point near the terminus of the sheet 40 to the head of the bed. One side edge of the sheet 40 is anchored as at 42 to a side rail 21 while its opposite edge is detachably secured as at 43 to the opposite side rail 21. The sheet 41 is likewise anchored to the frame 33 and it will thus be seen that when the lift frame is elevated from the bed and mattress 19, the weight of the patient will be sustained on the lift sheets.

In use the frame is deposited on the bed as suggested in the drawings and the end bars 22 and 34 are adjusted properly to support the frame on the side rails 13 and supporting hooks 26. The trunk supporting and elevating frame 33 will of course be deposited toward the head of the bed so that the pivots 34 coincide substantially with the pivots 14. A patient may then be placed on the bed in the ordinary manner and when it is desired to elevate or transfer him for any purpose, it is only necessary to couple suitable elevating cables to the eyes 30 and lift the frame and the patient clear of the bed so that his weight is supported on the lift sheets 40 and 41. If the patient is in a sitting posture when it is desired to lift or transfer him the notched bars 37 are adjusted with relation to the pins 39 so as to sustain the frame 33 at the desired angle and the patient may be lifted without altering his position. Likewise the patient may be replaced on the bed without changing his position and when it is desired to raise or lower the frame 33, the arms 37 are disengaged from the pins 39 so that the frame 33 will rest on the frame 15. The raising or lowering of the

trunk of the patient may then be accomplished by merely turning the crank 17 and he may be gently returned to a prone position without suffering any serious discomfort.

While in the foregoing there has been shown and described the preferred embodiment of this invention it is to be understood that minor changes in the details of construction, combination and arrangement of parts may be resorted to without departing from the spirit and scope of the invention as claimed.

Having described this invention, what is claimed as new is:

In a hospital bed of the type which includes a bed frame embodying a horizontal limb supporting section, and a trunk supporting and elevating section pivotally connected to the limb supporting section to move upwardly in a vertical arc from a horizontal position aligned with the limb supporting section, and means carried by the bed frame and connected to the trunk supporting section to move said trunk supporting section through said vertical arc, means to support a patient so that when the bed is moved the patient is held in a position substantially identical with that occupied by him while on the bed, said means comprising a lift frame adapted to rest on the bed frame, a trunk supporting and elevating frame pivoted to the lift frame adjacent the pivotal connection between the limb supporting sections of the bed frame and the trunk supporting section thereof, so that said trunk supporting and elevating frame is arranged to move in a vertical arc with the trunk supporting and elevating section, said trunk supporting and elevating frame being adjustably connected with the lift frame to hold the trunk supporting and elevating frame in elevating position during the removal of the lift frame from the bed frame, and lift sheets carried by the lift frame and the trunk supporting and elevating frame, said sheets overlying a mattress supported on the bed frame and supporting a patient on the lift frame when it is removed from the bed.

GEORGE Q. RUST.
